(57) **CLAIM**

The ornamental design for a riser pad for an equestrian saddle, as shown and described.

DESCRIPTION

FIG. 1 is a front perspective view of a riser pad for an equestrian saddle showing my new design.

FIG. 2 is a right side elevational view thereof, the left side elevational view being a mirror image thereof.

FIG. 3 is a front elevational view thereof.

FIG. 4 is a rear elevational view thereof.

FIG. 5 is a top plan view thereof; and,

FIG. 6 is a bottom plan view thereof.

The broken lines in the figures are for illustrative purposes only and form no part of the claimed design.
